UNITED STATES PATENT OFFICE.

STEPHEN N. SMITH, OF PROVIDENCE, RHODE ISLAND.

MANUFACTURE OF LACING-STUDS.

SPECIFICATION forming part of Letters Patent No. 498,315, dated May 30, 1893.

Application filed August 5, 1892. Serial No. 442,234. (No model.)

To all whom it may concern:

Be it known that I, STEPHEN N. SMITH, a citizen of the United States of America, residing at Providence, in the county of Providence and State of Rhode Island, have invented certain new and useful Improvements in the Manufacture of Lacing-Studs, of which the following is a specification.

My invention relates to the manufacture of 10 lacing studs of that class in which my base plate is provided with attaching prongs, to connect it to the leather or fabric, and is combined with a neck or head which forms the hook or lacing part of the stud. Such studs 15 have been heretofore made in many forms, and my invention consists first in an improvement in the art, which is a new and improved mode of making such studs; and second, in an improved special form of stud.

20 My said invention is illustrated in the accompanying drawings, in which—

Figure 1 shows in side elevation the form of the wire or blank out of which my stud is formed. Fig. 2 is a similar view of the blank 25 when the part forming the head, base and neck has been upset. Fig. 3 shows a cross section on line $x-x$ of Fig. 2. Fig. 4 shows a side elevation of the blank, with the head of the blank milled out. Fig. 5 shows the finished form of the shank. Fig. 6 is a side view of the completed stud.

In the drawings, the piece of wire shown in Fig. 1 is of the proper length to form the stud, and in diameter equal to the diameter 35 of the shank. In the first step of the process, one end of the blank is upset, and is formed thereby into a larger cylinder, in length equal to the outside measure from the bottom of the

base plate to the top of the head of the finished stud. The remaining part is of the 40 length required for the prongs and is of the original diameter of the wire, which is less than the upset part, with a shoulder in plane at right angles to the shank, this form being shown in Figs. 2 and 3. I therefore, as a second step, mill out the solid blank-head laterally from one side, leaving a neck a , on the other, which connects the base b with the head c .

The third step of the process consists in 50 splitting the solid shank into two prongs, the milling out being widest at the points, and narrowing to the bottom of the base, leaving the inner faces of the prongs, which form the attaching shank, slightly diverging, as usual.

55 The second and third steps may be reversed in order. This process may be carried out by hand, with ordinary tools, but is practically performed by suitable machinery.

I claim—

60 The hereinbefore described method of making lacing studs, consisting in taking a piece of solid wire of the diameter of the finished shank, upsetting the upper end thereof concentrically of the base, milling the upset part 65 laterally to form the head, neck and base, and finally dividing the base by milling to the line of the upset portion, substantially as described.

70 In testimony whereof I affix my signature in presence of two witnesses.

STEPHEN N. SMITH.
